UNITED STATES PATENT OFFICE.

HARRY S. ABELL, OF MCLEAN, VIRGINIA.

GAME.

Application filed April 22, 1924. Serial No. 708,238.

This invention relates to games which involve the use of a large number of playing units as is the case in the use of the ordinary pack of playing cards.

The ordinary so-called playing cards consist of a pack of four sets of cards, each set containing 13 cards, and distinguished from other sets by figures such as hearts, diamonds, clubs and spades, the individual cards of each set being distinguished from each other by a numerical or other determining factor denoting its value relative to the other cards. These designations usually run numerically from one to ten inclusive, followed by the well known jack, queen and king face cards. The several sets are similar, except of different suits. In this way, each card is a member of two cross groups or dimensions. For instance, in the usual set of playing cards, the "five of diamonds" is a member of the cross group of "fives" of which there are four in number, one for each "color suit" and it is also the "five" member of the "diamond" cross group or dimension. In this way, in playing the several games, this card and every other card may be considered in, and consequently having values with respect to, these two cross groups or dimensions.

With the growth of card playing and the increased mental training and development of today, has come a demand for more complex games to meet this increased mental activity. Many methods of making the card games more complex have been used, a number of which require the use of a much greater number of cards, and some require additional equipment.

The term "dimension" as used in this specification is used not in a sense of measuring distance but as having a relative value and consequently analogous to distance measuring. As the members of the numerical cross group of a series of a suit in the ordinary pack of playing cards each bear relation one to the other in this group and as each card in this cross group or suit bears a relation to a similarly numbered or designated card in another cross group or suit it may be said, because of this relation, that in a color suit of the ordinary pack of playing cards, we have one dimension while in the pack we have two dimensions.

The primary object of this invention is the provision of an improved pack of playing cards or units.

Another object of this invention is the pro-

vision of a pack of playing cards or units each card or unit being a member of each of three cross groups or dimensions.

Another and further object of this invention is the provision of a pack of playing cards or units each card or unit having one characteristic or determining factor of each of three cross groups or dimensions.

Another and still further object of this invention is the provision of a pack of playing cards or units, having three cross groups or dimensions therein, the cards or units of each cross group or dimension having a characteristic which will identify their relative value in each cross group or dimension.

Another and still further object of this invention is the provision of a pack of playing cards or units having three groups or dimensions, the cards or units of each cross group or dimension being arranged in a relatively progressive order as to value in that cross group or dimension.

Referring to the drawing wherein is illustrated an embodiment of this invention,

Fig. 1 is a view of a suit of playing cards or other units where the color is kept the same—red—and the number, indicia and shape are changed.

Fig. 2 is a view of a similar set of playing units to those shown in Fig. 1 but being colored yellow.

Fig. 3 is a view of a similar set of playing units to those shown in Fig. 1 but being colored green.

Fig. 4 is a view of a similar set of playing units to those shown in Fig. 1 but being colored blue.

The pack which has been found to be convenient, and which is illustrated in the drawing, comprises sixty playing units such as cards. Each color suit as shown in Figs. 1 to 4, respectively, is illustrated as having fifteen units—five units in the circle suit, five in the square suit and five in the triangle suit. Each unit of any of the five units having the same color and shaped spots, has its number of spots so similarly shaped and repeated the required number of times to indicate its position in the series and its relative value in playing the game.

Considering the colors as having relative value according to their respective places in the series of the seven primary colors as usually given, blue would have the lowest value followed by green, then yellow and ending with red, to which we would assign the

greatest value in the series. Of course, the colors could be arranged in arbitrary order if desirable.

Considering the spots which have been selected for illustration, the triangle square and circle, and giving them a value according to the number of their sides, the circle being, of course, considered as a polygon of an infinite number of sides, the triangle would have the lowest value, the square next and the circle the greatest value.

Since the three forms of spots—circles squares and triangles—occur in the same color suit cross group or dimension and since the circles have greater value than the squares and the squares a greater value than the triangles, it follows that the circle one spot will have greater value than the square five spot and the square one spot will have a greater value than the triangle five spot.

Considering a spot suit cross group or dimension as might be desirable in some games, we have all of the playing units having the same shaped spot as, for instance, the circle. Since the red units are higher in value than the yellow, the yellow than the green and the green than the blue, it follows that the red circle one spot will be higher in value than the yellow circle five spot, the yellow circle one spot is higher in value than the green circle five spot and the green circle one spot is higher in value than the blue circle five spot.

If now we consider all of the twelve units having the same number of spots, as for instance, the five spots of all colors, we find that, since, in value, red is greater than yellow, yellow than green and green than blue and remembering that circles are greater in value than squares and squares than triangles, we have, in order of value, in the blue, the triangle, square and circle, in the green, the triangle, square and circle, in the yellow, the triangle, square and circle, in the red, the triangle, square and circle, all in their relative order of value, the blue five triangle at the lowest value of the fives and the red five circle at the highest.

It will thus be observed that there are four suits, in the color suit cross group or dimension, of fifteen playing units each, three suits in the shape cross group or dimension of twenty playing units each and five suits in the number cross group or dimension of twelve playing units each.

One of the games that may be played with this pack and which is called "allez honors" is played as follows:—

Four players playing, the opposites being partners, one who is chosen by courtesy, deals all of the playing units as in cards, beginning to deal at his left. The deal thereafter rotates, in order, each time to the left. Instead of dealing, as for instance, if the playing units are made in the shape

of dominoes, the units after being shuffled will simply be distributed in a well known manner, fifteen to each player.

The dealer after examining his playing units, bids the number of tricks he contracts to take at the same time announcing the suit, as a color, which he makes trumps; or he may announce it as "no trumps" if he so desires. Each player may then, in turn, in the order of dealing, have an opportunity for bidding. He must, however, if he bids, increase the next previous bid made and, of course, may choose his own trump without regard to any previous bidder's selection of a trump. However, a player may bid over his partner's previous bid in the same suit, in which case, the original bidder in that suit plays the hand and is considered the successful bidder.

After the bidding is terminated, the partner of the successful bidder lays his hand, on the table, with the faces of the units exposed. This takes place after the first lead is made. This hand is played in turn by the successful bidder, he, of course, playing his own hand also. The player to the left of the successful bidder leads first after which the taker of the trick leads. After the lead is made, subsequent players must play units of the same color, if possible, but are not limited to the design. If a player has no units of this color, he will play either a trump or will "throw away" from an off-suit at his election.

Each color suit is divided into a high third, a middle third, and a low third. The high third is composed of playing units of the circle design, the middle third is composed of playing units of the square design and the low third is composed of playing units of the triangle design. The five circle is the highest unit of the color suit and the one triangle is the lowest. The one circle is higher than the five square and the one square is higher than the five triangle.

A trick is taken by the player playing the highest unit of the color suit led; as above shown, although any trump is higher than any suit card.

Game points.

Each trick taken counts one game point for the taker thereof whether bidder or not. A total of twenty game points by any partners completes a game. Two games out of three consecutive games, doubles the honor points for the winner thereof. The total score is the sum of the game points and honor points. The honor count is made as follows:—

Honor score.

Each trick has four playing units, one having been played from each hand. The permutations and combinations among these

four playing units count as honors and score for the taker of the trick.

Honor score points.

Points

5	1 pair	2
	3 of a kind	6
	4 of a kind	12

In these, the number and design on each 10 playing unit must be the same, although the color will, of course, vary i. e., a four red circle and a four green circle in a trick count two while a four red circle and a four red triangle count nothing.

15 Sequence 3 or 4 points.

In this, the three of four playing units must have the same design of spot and the numbers must be in sequence without regard 20 to color.

Flush 4 points.

In this, the four playing units of the trick, must all be of the same color without 25 regard to design or number of spots.

Similarity 3 points.

In this, three playing units in the trick 30 or combinations of three playing units in the trick must have the same number of spots in order to count, but the spots on the three units must be of a different design. If of the same kind, they become three of a kind.

35 Nines 2 points.

In this, any combinations of playing units in which the number of spots add to a total of nine, counts 2 points regardless of color or design.

40 Honor score is counted at the completion of play of each trick. Play is continued until all fifteen tricks are taken at which time game points are counted. The end of a

45 game is determined by completion of the playing of the hand in which any pair of partners secures a score of at least 20 game points. If in this hand both pairs of play-

50 ers have 20 or more game points, the game is won by the successful bidder provided he takes a number of tricks in this hand equal to his bid.

Penalties.

55 A successful bidder who does not take the number of tricks equal to his bid, forfeits all game points in the hand being played and his honor score for this hand goes to his opponents. The hand in this case must, 60 therefore, be played out.

Having described my invention, what I claim is:—

1. A game having a plurality of compo-

nent playing units, the units being divided into three cross groups, each group being designated by a determining factor, the component units of one cross group having determining factors identifying them as being in a definite relation to each of the other cross groups.

2. A game having a plurality of component playing units, arranged in three cross groups, each unit being a member of each of the three cross groups, the members of each cross group being arranged in relatively progressive order as to value in that cross group.

3. A game having component playing units, a plurality of the units being grouped in three cross groups, each of these units being a member of each of the three cross groups, one of the cross groups having a relativity indicated by different colors and another cross group having a relativity indicated by different designs.

4. A game having component playing units, a plurality of the units being grouped in three cross groups, each of these units being a member of each of the three cross groups, one of the cross groups having a relativity indicated by different colors, another cross group having a relativity indicated by indicia showing numerical values and the other cross group having a relativity indicated by different forms.

5. A game having component playing units, a plurality of the units being grouped in three cross groups, each of these units being a member of each of the three cross groups, the units of the respective cross groups having their determining factors expressed by figures of different shapes in one cross group, of different colors in another cross group and by a repetition of the appearance of the figures a different number of times in the other cross group.

6. A game comprising component playing units arranged in three groups or suits, each group or suit having different determining factors, each unit of each suit having a counterpart throughout its group and differing only by the factor of its own group.

7. A game having component playing units arranged in three cross groups or suits, each group having its own characteristics or determining factors, each of the units being a member of the three cross groups or suits, the total number of component units so grouped being the product of the numbers of units in each of the cross groups or suits.

In testimony whereof I hereunto affix my signature.

HARRY S. ABELL.
